(57) **CLAIM**

The ornamental design for a measuring device for measuring point-to-point distances and inclinations on a vehicle chassis and body, as shown and described.

DESCRIPTION

FIG. 1 is a front perspective view of the measuring device for measuring point-to-point distances and inclinations on a vehicle chassis and body according to my design; FIG. 2 is another front perspective view thereof; FIG. 3 is a rear perspective view thereof; FIG. 4 is another rear perspective view thereof; FIG. 5 is a front perspective view thereof with the measuring device for measuring point-to-point distances and inclinations on a vehicle chassis and body telescoped; and, FIG. 6 is rear perspective view thereof with the measuring device for measuring point-to-point distances and inclinations on a vehicle chassis and body telescoped.
